UNITED STATES PATENT OFFICE.

HENRY L. GULLINE, OF MONTREAL, QUEBEC, CANADA, ASSIGNOR OF ONE-HALF TO
JOHN HYDE, OF WEMOUNT, QUEBEC, CANADA.

CALENDAR.

Application filed May 12, 1924. Serial No. 712,661.

To all whom it may concern:

Be it known that I, HENRY L. GULLINE, of the city of Montreal, Province of Quebec, Dominion of Canada, a subject of the King of Great Britain, have invented certain new and useful Improvements in Calendars; and I do hereby declare that the following is a full, clear, and exact description thereof.

My invention relates particularly to perpetual calendars and has for its object to apply the structural features of the calendars disclosed in my Patents Nos. 1,378,857 and 1,448,293 to a segmental calendar of quadrantal form for the purpose of simplifying the mechanism and improving the display.

For full comprehension, however, of my invention reference must be had to the accompanying drawings in which similar reference characters indicate the same parts and wherein:

Figure 1 is a face view of my improved calendar;

Figure 2 is a similar view to Figure 1 with the face plate broken away to expose the operating mechanism as viewed from the front;

Figure 3 is an elevation of the back of the calendar;

Figure 4 is a similar view to Figure 3 with the back plate broken away to illustrate the operating mechanism as viewed from the rear;

Figure 5 is a detail view of one of the screens;

Figure 6 is a detail view of another screen;

Figure 7 is a detail view of a reinforcement plate, and

Figure 8 is a transverse sectional view taken on line 8--8 Figure 1.

Figure 9 is a detail view of the face plate;

Figure 10 is a sectional view taken on line 10--10 Figure 2;

Figure 11 is a sectional view taken on line 11--11 Figure 2; and

Figure 12 is a sectional view taken on line 12--12 Figure 2.

My improved calendar mechanism is contained in the case disclosed in my United States Patent No. 1,459,052 which consists essentially of a back *b* and *g* an unbroken transparent front *c* held together by a flange *d*.

According to my present invention the periphery of the face plate *c* of the calendar

is cut away as at *f*. This *f* cut is made concentrically to the centre of the face plate and its depth is equal to one half of the width of the retaining flange *d* on the back. The top *g* of the face plate is oblate, the center 10 being lowered a distance equal to half the width of the flange. The sides of this figure are flattened as at *h*. The purpose of this particular form is to permit a face plate to be used which is large enough to be retained in place by the flange *d* and which may be easily inserted into place beneath the flange without mutilating the face plate. The top and sides of the face plate are first inserted beneath the flange and then the bottom is sprung into place beneath the same, the notch *f* making it possible to spring the bottom under the flange.

The day numbers are printed on a semi-circular card *j* in thirteen radial columns 75 containing respectively the following numbers:

1	2	3	4	5	6	7
2	3	4	5	6	7	8
9	10	11	12	13	14	15
16	17	18	19	20	21	22
23	24	25	26	27	28	29
30	31					

These radial columns are in semi-circular arrangement and an opening *k* in the face plate is made complementary by being cut to quadrantal form, and in order to accommodate figures at the extreme lower ends at the left hand side of the series of columns 85 an extension *m* of the opening is provided by a notch in the outer curved side of the latter. This card *j* is pivoted centrally as at *n* to the back and it is operated by a slide button *o* fixed in a radial plate *p* which

reinforces and stiffens the card in addition to providing for the rigid attachment of the button and reinforced pivoted connection. A screen *r* for covering the day numbers over 28 in the next to lowest row, is 100 provided by an angular radial arm the radial portion *s* being pivoted at one end on the same central pivot as the day number card *j*; while the angular portion *t* is curved concentrically with the row of figures it is 105 designed to partially cover. This curved arm protrudes through a slot 50 in the card from rear to front and is operated by a button *u* fixed in the arm *s*. The movement of this arm, and the screen, is limited 110

by a lateral arm *v* concentric to the screen and slotted as at *w*. This slot accommodates the button *o* and by this arrangement the extent of movement of the screen is limited in 5 both directions. The screen is further limited by a slot in the back of the case. This slot is indicated at 2 and has one end reduced in width as at 3 to present shoulders 4. These shoulders limit the movement in 10 one direction of the button *o* the movement in the opposite direction being limited by the opposite end of the slot; while the end of the narrowed portion of the slot limits the movement in that direction of the button 15 *u* of the screen. A second screen 5 serves to cover either or both of the day numbers 30 and 31 in the lowest row. This screen is located between the day number card *j* and the face plate *e* the back having a 20 segmental slot 6 concentric with the pivot of the day number card *j*. The screen is curved and of substantially oblong form and long enough to cover both numbers 30 and 31. It has a pair of buttons 7 and 8 25 respectively fixed rigidly therein and protruding through the slot with their heads overlapping the outside edges of the slot. These buttons are so relatively spaced that they limit the movement of the screen in 30 both directions, and the width and particular arrangement of the screen relatively to the card *j* is such that its lower edge extends below the card and its upper edge is slightly lower than the normal lower edge 35 of the opening *k* in the face plate. The width of this screen permits the points of connection of the operating buttons to be concealed behind the lower portion of the face plate when exposed in screening position, while the entire screen is also concealed behind the lower part of the face 40 plate when not in use.

The month card 15 is circular in form and the names of the months with the number 45 of days in each are arranged in circumferential series, "February" being twice indicated. This card is pivoted in the back plate and carried by an operating turn-button 20 the shank 21 of which protrudes 50 through the back and has the card riveted to it as shown in Figure 8, the hollow stem 22 facilitating the rivet connection. The card is reinforced on both sides at the rivet by a pair of wide washers 26 and 27. 55 A relatively small ornamental opening 30 is cut through the face plate above the main opening *k* to expose the month indications.

What I claim is as follows:

1. A perpetual calendar consisting of a 60 closed case comprising a face plate, an unbroken transparent front member completely covering the face plate, and a rigid back having a peripheral flange overlapping the peripheral portion of the transparent front member, a segmental card bearing day num-

bers pivotally mounted within the case, said day numbers being visible through a segmental opening in the front plate, means for turning said card on its pivot consisting of a button connected to said day card and 70 projecting through a slot in the back plate curved concentrically through said pivot, a second card pivoted eccentrically relatively to the day number card and bearing month names, said month names being visible 75 through an opening in the front plate, means for turning the day number card on its pivot, said means consisting of a turn button projecting through the back plate and connected to the month card, the axis of 80 said turn button coinciding with the pivot point of the card and a pair of movable screens for concealing certain of the day numbers and means for moving said screens, said means consisting of buttons projecting 85 through slots in the back plate, said slots being curved concentrically through the pivot point of the day number card.

2. In a perpetual calendar the combination of a case comprising a back and a face plate, a pivoted day number card, reinforcement means mounted upon the card and extending from the pivot thereof outwardly in a radial direction, manually operable means for rotating the card on its pivot, said means being mounted upon said reinforcement means, and a screen for concealing the end numbers of a month, said screen consisting of a unitary member located at the rear of the card and comprising a radial portion, the inner end 90 of which is pivoted at the pivot of the card and an angular portion extending laterally from the outer end of the radial portion and curved concentrically to the row of numbers to be concealed thereby, said angular portion 95 protruding forwardly through an opening in the card and movable on its pivot relatively thereto, means for manually operating said screen and means coacting with the means for rotating the card for the purpose of limiting the extent of movement of the screen.

3. In a perpetual calendar the combination of a case comprising a back and a face plate, a pivoted day number card, reinforcement means mounted upon the card and extending from the pivot thereof outwardly in a radial direction, manually operable means for rotating the card on its pivot, said means being mounted upon said reinforcement means, and a screen for concealing the end numbers of a month, said screen consisting of a unitary member located at the rear of the card and comprising a radial portion, the inner end of which is pivoted at the pivot of the card and an angular portion extending laterally from the outer end of the radial portion and curved concentrically to the row of numbers to be concealed thereby, said angular portion 115 120 125 130

- truding forwardly through an opening in the card and movable on its pivot relatively thereto, means for manually operating said screen independently of the card and means 5 coacting with the means for rotating the card for the purpose of limiting the extent of movement of the screen, said means consisting of a slotted arm formed integrally with the radial portion of the screen, the 10 means for manually rotating the card extending through said slot.
4. In a perpetual calendar the combination with a case comprising a face plate and a back having a curved slot therein of reduced width adjacent one end, a pivoted day 15 number card with numbers arranged in rows thereon concentric to the pivot, said face plate having an opening adapted to expose certain of the numbers, an operating button 20 secured to said card and protruding through the slot in the back plate, said button being too large to enter the reduced portion of the slot, and a screen for concealing the end numbers of a month, said screen 25 consisting of a unitary member comprising a radial portion, the inner end of which is pivoted at the pivot of the day card and an angular portion which extends laterally from the outer end of the radial portion and is curved 30 concentrically with the row of numbers to be concealed by it and an arm extending laterally from the radial portion and formed integrally therewith, said arm being slotted to permit the passage therethrough of the 35 said button, and a second button for manually operating the screen, said second button extending through the slot in the back plate and being adapted to enter the narrower width of the latter.
6. In a perpetual calendar the combination with a case comprising a face plate and a back having a curved slot therein of reduced width adjacent one end, a pivoted day 40 number card of segmental form with numbers arranged in rows thereon concentric to the pivot, said face plate having an opening adapted to expose certain of the numbers, a reinforcement member mounted upon said card and extending from the pivot 45 thereof outwardly in a radial direction, an operating button secured to said card and protruding through the slot in the back plate, said button being too large to enter the reduced portion of the slot and a screen 50 for concealing the end numbers of a month, said screen consisting of a unitary member comprising a radial portion, the inner end of which is pivoted at the pivot of the day card and an angular portion which extends laterally from the outer end of the radial portion and is curved 55 concentrically with the row of numbers to be concealed by it and an arm extending laterally from the radial portion and formed integrally therewith, said arm being slotted to permit the passage therethrough of the 60 said button, and a second button for manually operating the screen, said second button extending through the slot in the back plate and being adapted to enter the narrower width of the latter.
5. In a perpetual calendar the combination with a case comprising a face plate and a back having a curved slot therein of reduced width adjacent one end, a pivoted day 65 number card with numbers arranged in rows thereon concentric to the pivot, said face plate having an opening adapted to expose certain of the numbers, a reinforcement member mounted upon said card and extending from the pivot 70 thereof outwardly in a radial direction, an operating button secured to said card and protruding through the slot in the back plate, said button being too large to enter the reduced portion of the slot and a screen 75 for concealing the end numbers of a month, said screen consisting of a unitary member comprising a radial portion, the inner end of which is pivoted at the pivot of the day card and an angular portion which extends laterally from the outer end of the radial portion and is curved 80 concentrically with the row of numbers to be concealed by it and an arm extending laterally from the radial portion and formed integrally therewith, said arm being slotted to permit the passage therethrough of the 85 said button, and a second button for manually operating the screen, said second button extending through the slot in the back plate and being adapted to enter the narrower width of the latter.
- 40 5. In a perpetual calendar the combination with a case comprising a face plate and a back having a curved slot therein of reduced width adjacent one end, a pivoted day 90 number card with numbers arranged in rows thereon concentric to the pivot, said face plate having an opening adapted to expose certain of the numbers, a reinforcement member mounted upon said card and extending from the pivot 95 thereof outwardly in a radial direction, an operating button secured to said card and protruding through the slot in the back plate, said button being too large to enter the reduced portion of the slot and a screen 100 for concealing the end numbers of a month, said screen consisting of a unitary member comprising a radial portion, the inner end of which is pivoted at the pivot of the day card and an angular portion which extends laterally from the outer end of the radial portion and is curved concentrically with the row of numbers to be concealed by it and an arm extending laterally from the radial portion and formed integrally therewith, said arm being slotted to permit the passage therethrough of the said button, and a second button for manually operating the screen, said second button extending through the slot in the back plate and being adapted to enter the narrower width of the latter.

In testimony whereof I have signed my name to this specification.

HENRY L. GULLINE.
